UNITED STATES PATENT OFFICE.

ROBERT F. DOHERTY, OF YONKERS, NEW YORK, ASSIGNOR TO THE ALEXANDER SMITH & SONS CARPET COMPANY, OF SAME PLACE.

DESIGN FOR CARPET.

SPECIFICATION forming part of Design No. 25,906, dated August 4, 1896.

Application filed June 18, 1896. Serial No. 596,072. Term of patent 3½ years.

To all whom it may concern:

Be it known that I, ROBERT F. DOHERTY, of Yonkers, county of Westchester, State of New York, have invented and produced a certain 5 new and original Design for Carpets, fully described and represented in the following specification and the accompanying drawing, forming a part of the same.

The design is intended to be worked into 10 or upon carpets or similar fabrics in such colors as may be desired; and I do hereby declare that the drawing accompanying this specification conveys to any one skilled in the art of carpet weaving and manufacture 15 a clear understanding of the same and is sufficient to enable such person to use my invention.

The characteristic features of the design are the prominent ornamental flower and leaf heads A on the ground B, with the interposed scrolls formed by branching stem and leaf figures.

What I claim as new, and desire to secure by Letters Patent, is—

The design for carpets, substantially as 25 shown and described.

In testimony whereof I have hereunto set my hand in the presence of two subscribing witnesses.

ROBERT F. DOHERTY.
